Primary Examiner — Paul D Bohannon

(57) **CLAIM**

The ornamental design for a beach chair with umbrella, as shown and described.

DESCRIPTION

FIG. 1 is front elevation view of a beach chair with umbrella showing my new design;

FIG. 2 is a rear elevational view thereof;

FIG. 3 is a left elevational view thereof;

FIG. 4 is a right elevational view thereof;

FIG. 5 is a top plan view thereof;

FIG. 6 is a bottom plan view thereof;

FIG. 7 is a perspective view thereof; and,

FIG. 8 is a perspective view of use state thereof.

The broken lines in the drawings illustrate portions of the article that form no part of the claimed design.

1 Claim, 8 Drawing Sheets
